PNEUMATIC TIRE

Laurence Porten, 5836 Clark Ave. Extension,
Bethel Park, Pa. 19507

Filed May 22, 1968, Ser. No. 12,040

Term of patent 14 years

Int. Cl. D12—14

U.S. Cl. D90—20

FIGURE 1 is an isometric view of a pneumatic tire embodying my new design;

FIGURE 2 is a transverse section taken along the line II—II of FIGURE 1, illustrating my new design; and

FIGURE 3 is a transverse section taken along the line III—III of FIGURE 1 to illustrate the conventional, continuous circumferential ribbing.

The dominant features of my design reside in the portions shown in full lines, and my tire design is characterized by a deep groove tread of circumferentially-spaced, straight, cross grooves, of a centrally-located circular groove associated with and open to each cross groove, and of elliptical grooving defined by pairs of intersecting curve segments that are located in the spacing between cross grooves; all of the grooving of my design has substantially the same tire tread depth at points on the same circumferential plane of the tread.

It is to be understood that the tread design as shown in the foreground in FIGURE 1 continues throughout the circumference of the tire.

I claim:

The ornamental design for a pneumatic tire, substantially as shown and described.
